INVENTOR.

David W. Glascock

UNITED STATES PATENT OFFICE.

DANIEL W. GLASCOCK, OF STOCKTON, CALIFORNIA.

LOGGING DEVICE.

Application filed December 27, 1921. Serial No. 525,202.

To all whom it may concern:

Be it known that I, DANIEL W. GLASCOCK, a citizen of the United States, residing at the city of Stockton, county of San Joaquin, 5 and State of California, have invented new and useful Improvements in Logging Devices, of which the following is a specification.

This invention relates to a logging device 10 and has particular reference to a low tractor logging wheel device equipped with novel means for lifting and holding logs of varying diameters.

The primary object of this invention is to 15 provide a device of the character described so constructed as to operate in confined places or on rough hilly ground whereby I attain high clearance on a low axle construction.

20 An additional object is to provide a novel type of main frame adapted to support the axles of the device with the axle so supported from both sides that the danger of the axle breaking is reduced to a minimum.

25 A further object of this invention is to provide a device of the character described, which is comparatively simple in construction, inexpensive to manufacture, positive in action and highly serviceable and efficient 30 in use.

Other objects and advantages will be apparent during the course of the following description.

In the accompanying drawings forming 35 a part of this specification, and in which like characters are employed to designate like parts throughout the same—

Fig. 1 is a side of my tractor logging wheeled device.

40 Fig. 2 is a section on line 2—2 of Fig. 1.

Fig. 3 is a top plan view of the device.

Fig. 4 is a sectional view on line Y—Y of Fig. 3.

45 Among other elements my improvement comprises a tongue A, arranged between inner rearwardly extending rods B and outer rearwardly and downwardly extending rods B^x, each of the said rods comprising threaded sections as illustrated joined 50 by a turnbuckle B^z. The outer downwardly and rearwardly extending rods B^x afford bearings M for the outer ends of the axles P of wheels C.

55 The main frame of the machine is made preferably of structural steel and includes

a beam D to which the rear ends of the inner rods B are connected as shown in Figures 1 and 3. Said frame also includes two plates R, fixed to said beam D, forming an arch and trussing the main frame and 60 affording bearings for the inner ends of the axles P, as shown in Fig. 2.

These plates R are spaced apart the proper distance to allow a lifting chain S to pass freely up and down through guides 65 T at the lower ends of the plates R. Said guides serve to receive and maintain in spaced relation the pendent portions of the chain S, and thereby operate to keep the chain in place, and also to provide means 70 for fastening the axles P at or near the lower ends of the plates R as shown in Fig. 2.

On the ends of the beam D are pendent 75 brackets B^w extending down to and receiving the outer portions of the axles P to rigidly support the same as shown in Fig. 2.

Fixed to and extending forwardly from the beam D are hounds J which serve to brace and lend increased strength to the main frame. These hounds are fixedly connected at their forward ends to a cross member 20 which cross member forms a guide 21 for the tongue A as shown in Figure 4 and also serves for the connection of the forward ends of the rods B and B^x. In virtue of the said rods including turnbuckles B^z as described, the machine may be adjusted to any position forward or back, 80 so as to balance the load for any height of tractor.

On the top of the beam D are six bracket 85 bearings, the inner bearings G having anti-friction rollers G^x placed at such a position as to allow the tongue A (see Fig. 1) to pass through under them freely. Carried by the beam D and disposed under the tongue A is an anti-friction roller D^x. (See dotted lines in Figure 2.)

Journalized in the bearings G is a shaft 100 H with a spur gear I keyed or fastened in its center as shown in Fig. 2.

On top of the hitch tongue A is a rack 105 A^x with teeth engaging with the gear I, as shown in Fig. 1, the object of the same being that when the tractor moves forward the rack on the hitch tongue A (Fig. 1) will also move forward, causing the gear to rotate turning the shaft, thus winding the chain, which is arranged to wind up on said 110

shaft, causing the logs around which the chain has been locked, to be lifted from the ground as shown in Fig. 2.

Carried by a rear pendent portion 30 on 5 the tongue A is a buffer 31, opposed to the rear side of the beam D and yieldingly maintained in the position illustrated through the medium of a coil spring 32 mounted on the buffer and interposed between the said rear portion 30 and the head or forward enlargement of the buffer. Manifestly the said buffer will serve on forward movement of the tongue A relative to the main frame of the apparatus to bring 10 up against the rear side of the beam D and thereby absorb shock and jar.

From the foregoing description considered in connection with the accompanying drawings, it will be evident that I have devised a highly efficient device that will serve 20 to lift and hold a plurality of logs of varying diameters.

It is to be understood that the form of my invention herewith shown and described 25 is to be taken as a preferred example of the same, and that various changes in the shape, size and arrangement of parts may be resorted to without departing from the spirit of the invention or the scope of the 30 subjoined claims.

Having described my invention, what I claim and desire to secure by Letters-Patent, is:—

1. In a logging device, a beam with bearings thereon and with pendent brackets at its 35 ends, plates fixed to and depending from said pendent brackets, axles carried by said brackets and plates and spaced apart, wheels mounted on said axles and disposed between the pendent brackets and said depending plates, a transverse member disposed in front of said beam, rods having turnbuckles and interposed between and connecting the outer ends of the axles and said transverse member, rods having turnbuckles and interposed between and connecting the beam and the transverse member, a shaft in the said bearings on the beam 40 and adapted for the winding of the ends of chain and having a gear fixed on the shaft and arranged between the innermost of said bearings, hounds interposed between and connecting the beam and the transverse member, and a tongue guided between said innermost bearings and also guided by the transverse member and having a rack meshed with said gear.

2. In a logging device, a beam with bearings thereon and with pendent brackets at its 45 ends, plates fixed to and depending from said pendent brackets, axles carried by said brackets and plates and spaced apart, wheels mounted on said axles and disposed

between the pendent brackets and said depending plates, a transverse member disposed in front of said beam, rods having turnbuckles and interposed between and connecting the outer ends of the axles and 50 said transverse member, rods having turnbuckles and interposed between and connecting the beam and the transverse member, a shaft in the said bearings on the beam and adapted for the winding of the ends of 55 chain and having a gear fixed on the shaft and arranged between the innermost of said bearings, hounds interposed between and connecting the beam and the transverse member, a tongue guided between said bearings and also guided by the transverse member 60 and having a rack meshed with said gear, and guides on the said depending plates to receive and to retain in spaced relation the side portions of the said chain.

3. In a logging device, a beam with bearings thereon and with pendent brackets at its ends, plates fixed to and depending from the beam and spaced inwardly from said pendent brackets, axles carried by said brackets and plates and spaced apart, wheels mounted on said axles and disposed between the pendent brackets and said depending plates, a transverse member disposed in front of said beam and connected 65 with the beam and axles, a shaft in said bearings on the beam and adapted to wind the ends of a chain and having a gear fixed on the shaft, and a tongue guided by the beam and also guided by the transverse member and having a rack meshed with said gear.

4. In a logging device, a beam with bearings thereon and with pendent brackets at its ends, plates fixed to and depending from the beam and spaced inwardly from said pendent brackets, axles carried by said brackets and plates and spaced apart, wheels mounted on said axles and disposed between the pendent brackets and said depending plates, a transverse member disposed in front of said beam and connected with the beam and axles, a shaft in said bearings on the beam and adapted to wind the ends of a chain and having a gear fixed on the shaft, and a tongue guided by the beam and also guided by the transverse member and having a rack meshed with said gear; the said depending plates being equipped with chain guides to receive the upwardly extending portions of the chain and to hold said portions apart.

5. In a logging device, the combination of a wheeled frame, cable winding means on the frame and including a spur gear, and a tongue guided by and movable relative to the frame and having a rack meshed with said spur gear whereby endwise movement of the tongue relative to the frame will be attended by operation of said cable winding means.

6. In a logging device, the combination of a main frame having pairs of pendant portions, the inner portions of the pairs spaced apart to form between them an arch, log supporting means carried by the frame, axles disposed at opposite sides of said arch and each carried by one pair of said depending portions, wheels mounted on said axles and disposed one wheel between the depending portions of each pair; the said frame including a beam carrying said depending portions and also including a transverse member spaced in front of the beam and connected with the beam and also connected with the outer ends of the axles, and the latter connections adjustable as to length. 10 15

DANIEL W. GLASCOCK.
